COMBINATION WRENCH AND SCREW
DRIVER

Paul M. Rogers, Balboa Island, Calif.

Application February 19, 1946, Serial No. 648,746

1 Claim. (Cl. 81—56)

1

This invention relates to a combination tool designed to take the place of the conventional screw-driver and socket wrench and has for its principal object the provision of an improved tool wherein the functions of this screw-driver and wrench are combined in a single structure.

A further object of the invention is to provide a combination tool in which the wrench element and the screw-driver element may be both operated simultaneously with a single hand, thus leaving the other hand free to operate any measuring or calibrating equipment which may be required.

The features and advantages of the present invention will be readily understood if it is considered in terms of the common operation of setting an adjustment screw which is held in place by a jam nut. Such a combination of adjustment screw and jam nut is frequently found in the tappet valve adjustment of an internal combustion engine. In present practice the fitting is made by rotating the adjustment screw with a screw driver until the proper clearance is obtained as indicated by a feeler gauge which is manipulated with the other hand. Once this is done the gauge is laid aside and the jam nut is tightened with a wrench, while the screw adjustment is held with a screw driver. It is then necessary to put down the wrench and check the clearance with the gauge; an operation which may have to be repeated several times until the proper clearance (as determined by the adjustment screw) and the correct locking action (which results from the rotation of the jam nut) is obtained.

The present invention overcomes this difficulty by providing a combination tool of a design such that a screw-driver bit may be rotated with one motion of the hand while the wrench is manipulated by a different movement of the same hand. In this way, the other hand is left free at all times, which means that either the jam nut or the adjustment screw or both may be rotated together or in any relation one to the other while gauging the setting with the other hand. The result is a more rapid and accurate adjustment of the screw and jam nut.

In accordance with the present invention a socket wrench is provided with a screw-driver bit located centrally within the socket and arranged so that it may be independently driven in either direction by rotation of the grip located on the wrench handle. In this way both the wrench and the screw driver bit may be operated by a single hand.

The invention will be better understood from 55 the tool is placed over the jam nut which fits

2

the following description, considered in conjunction with the accompanying drawing, in which like numerals denote like parts.

Figure 1 is a side elevation of the combination tool embodying the present invention.

Figure 2 is a central vertical longitudinal section of the tool shown in Figure 1.

Figure 3 is a view of the end portion of the tool looking from the bottom.

- 10 The tool shown in the drawing, Figures 1 and 2, comprises a hand grip 10 and a head 11 which are united by a handle 12. The grip 10 is arranged telescopically on the handle 12 in such a manner that it may be turned about it.
- 15 Located centrally within the hollow handle is a shaft 13 which is rigidly affixed—by welding in the present example—to the grip 10. A bevel drive gear 14 is permanently attached (as by welding) to the opposite end of shaft 13 and is provided with a collar 15 which, being slightly smaller in diameter than the internal diameter of handle 12, functions as a bearing to support the opposite end of shaft 13 which is nevertheless free to rotate within the handle by turning grip 10. Since gear 14 is larger than the internal diameter of handle 12 it also serves to prevent grip 10 from sliding off the end of the handle since shaft 13 acts as a tie rod.

The opening in the head 11 of the tool is fitted 30 with a contoured barrel 16 of hexagonal or other shape which is suitable for gripping a machine nut or similar locking device. Handle 12, hand grip 10 and head 11 are the three elements which make up a socket wrench.

35 In addition, however, there is located within the head 11 a second bevel gear 17 which meshes with and is driven by bevel gear 14 and is so arranged that its axis of rotation passes centrally through the opening in contoured barrel 16.

40 The screw-driver portion of the tool comprises a bit 18, a stem 19 of non-circular section which corresponds to the shape of a centrally located opening within gear 17 and is of such clearance that it may be readily moved longitudinally within 45 the head 11 of the tool but because of the shape of its cross-section is keyed to gear 17 so that it must rotate with it. The boss 20 at the end of the screw-driver stem serves merely to prevent the screw-driver portion from falling out of the head of the wrench and the widened bit 18 serves a similar function inasmuch as it is wider than the opening in gear 17.

The operation of the tool will be apparent from the above description. In use the head 11 of

within contoured barrel 16. The hand grip 10 is then rotated, actuating gears 14 and 17 and through them the screw driver bit which will fall into the slotted head of the screw when it meshes with it. Now that the tool has been positioned with both the adjustment screw and the jam nut, the screw may be rotated in either direction by twisting the grip about the handle while the jam nut may be loosened or tightened by rotating the entire tool with the head of the tool as the center of rotation. It is apparent that either the jam nut or the adjustment screw can be rotated independently of the other and that only one hand is necessary for any combination of movements.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. For example, the contoured barrel 16 may be removable so that other inserts can be used corresponding to a wide range of sizes of jam nuts.

What I claim is:

A combination tool comprising a head, a hol-

low handle and a tubular hand grip, the handle being welded to the head, the interior of the head being shaped to serve as a socket wrench, a screwdriver bit located within the head, the longitudinal axis of the head coinciding with the axis of the screwdriver bit and means for rotating the screwdriver bit relative to the head, said means comprising a bevel gear and a shaft located within the hollow handle, said bevel gear being rigidly affixed to the shaft which is actuated by rotation of the tubular hand grip about the handle and a second bevel gear to which the screwdriver bit is keyed to permit longitudinal movement of the screwdriver bit, the second bevel gear being driven by the first bevel gear.
